UNITED STATES PATENT OFFICE.

JAMES ANDERSON COULTER, OF INGERSOLL, CANADA.

DESIGN FOR A BICYCLE-HUB.

SPECIFICATION forming part of Design No. 28,702, dated May 24, 1898.

Application filed June 1, 1897. Serial No. 639,059. Term of patent 3½ years.

To all whom it may concern:

Be it known that I, JAMES ANDERSON COULTER, a subject of Her Majesty the Queen of Great Britain, residing at the town of Ingersoll, in the county of Oxford, in the Province of Ontario, Canada, have invented and produced a new and original Design for Bicycle-Hubs, of which the following is a specification, reference being had to the accompanying drawings, forming part thereof.

Figure 1 is a side elevation of a bicycle-hub, showing my new design. Fig. 2 is a longitudinal sectional view.

As shown in the drawings, the leading or material feature of my design consists of a swell or raised portion A, disposed or ar-

ranged between the spoke-hole flanges B, as shown in Fig. 1, the outer face of said swell or raised portion A being convex in longitudinal section, as shown in Fig. 2. 20

Having described my invention, what I claim as new, and desire to secure by Letters Patent, is—

The design for a bicycle-hub, substantially as herein shown and described. 25

In testimony whereof I have signed in the presence of the two undersigned witnesses.

JAMES ANDERSON COULTER.
